UNITED STATES PATENT OFFICE

2,529,792

STORM SASH VENTILATOR AND DEFLECTOR

William Wityaz and Frank Kendra, Chicago, Ill.

Application February 14, 1947, Serial No. 728,454

2 Claims. (Cl. 98—97)

1

This invention relates to a novel construction of ventilator and deflector for use with storm sashes and to provide means for permitting sufficient air through a storm sash to afford adequate ventilation and without opening the sash or removing it from its normal position within the window frame.

More particularly, it is an object of the invention to provide a ventilator and deflector capable of being readily applied to conventional storm sashes and which is of extremely simple construction involving a minimum of moving parts which may be applied to and used in conjunction with a storm sash with only a slight modification of the storm sash.

Still another object of the invention is to provide a device of the aforescribed character which will effectively deflect the air entering through the storm sash for eliminating a direct draft from the air when it is admitted through the conventional window sash and into a room or other enclosure.

Various other objects and advantages of the invention will hereinafter become more fully apparent from the following description of the drawings, illustrating a preferred embodiment thereof, and wherein:

Figure 1 is an elevational view, partly in vertical section looking toward a portion of the lower part of a storm sash and showing the ventilator and deflector mounted on the inner side thereof;

Figure 2 is a horizontal sectional view taken substantially along a plane as indicated by the line 2—2 of Figure 1;

Figure 3 is a vertical sectional view taken substantially along a plane as indicated by the line 3—3 of Figure 1;

Figure 4 is a view similar to Figure 3 but showing the ventilator in an open position and the draft deflector in an operative position;

Figure 5 is a vertical sectional view taken substantially along a plane as indicated by the line 5—5 of Figure 4;

Figure 6 is a plan view of one end of the deflector and closure; and

Figure 7 is an enlarged horizontal sectional view taken substantially along a plane as indicated by the line 7—7 of Figure 3.

Referring more specifically to the drawings, the ventilator and deflector in its entirety is designated generally 8 and for the purpose of illustrating the application and use thereof, the numeral 9 designates a portion of a window sill forming a part of a window frame, not shown, containing sliding sashes, a portion of the lower

2

sash 10 of which is illustrated in Figures 3 and 4. A storm window, a portion of which is illustrated and designated generally 12 is adapted to be mounted in any suitable manner in the window frame of which the sill 9 forms a part and has a bottom rail or bar 13 which rests upon the sill 9. As clearly illustrated in Figures 3 and 4, the storm window 12 is spaced outwardly a considerable distance from the lower sash 10 as is conventional in the mounting of storm windows and the ventilator and deflector 8 is adapted to be disposed in said space and secured to the inner side of the lower rail or bar 13 and when thus disposed is spaced a considerable distance outwardly with respect to the sash 10.

The ventilator and deflector 8 includes a housing, designated generally 14 comprising an outer wall 15 which is disposed substantially parallel to the rail 13 and provided with inturned portions 20 at the ends thereof forming side walls 16 which extend toward the rail 13 and which terminate in out-turned flanges 17 which abut against the inner side of the rail 13 and are secured thereto by suitable driven fastenings 18. The outer wall 15 is provided with an inturned lip or flange 19 at its bottom edge which is disposed in substantially the same plane as the bottom edges of the side walls 16. As best seen in Figures 3 and 4, the upper surface of the sill 9 on which the storm sash rail 13 rests slopes outwardly and downwardly and the housing 14 is secured to said rail so that the rounded corner formed by the juncture of the wall 15 and the lip 19 will rest on the upper surface of the sash 9 and will form the only portion of the housing 14 in engagement therewith.

The only modification of the storm sash which is required for use of the ventilator and deflector 8 is the provision of one or a plurality of openings 20 therein and which are located between the walls 16 in the bottom rail 13; three openings being shown in Figure 2, although it will be readily apparent that a greater or less number of openings could be provided or, if desired, a single elongated opening could be employed.

Each of the side walls 16 is provided with two longitudinally spaced rollers 21 and 22 which are disposed in substantially the same plane and which are journaled on pins or rivets 23 which are anchored in said side walls 16. As best illustrated in Figure 7, the pins or rivets 23 are preferably formed by a stem or shank 24 which extends through an opening 25 in its associated wall 16 which has a headed end 26 disposed on the outer side of the wall 16 and a threaded recess 27

opening outwardly of its shank end for receiving a threaded stem 28 which is removably mounted therein and provided with a head 29 at the outer end thereof for retaining the roller 21 or 22 in rotatable engagement with the stem 24.

The rollers 21 are disposed in longitudinal alignment and adjacent the inner side of the rail 13 and the rollers 22 are similarly aligned and disposed adjacent the wall 15 and spaced approximately the same distance therefrom as the 10 rollers 21 are spaced from said rail 13. A combination valve and deflector plate 30 has a lower portion which is adapted to be inserted between the rollers 21 and the inner side of the rail 13 or between the rollers 22 and the inner side of the wall 15. When in the first mentioned position, said lower portion of the plate 30 will be disposed between the rollers 21 and the inner side of the rail 13 and retained by said rollers 21 in tight engagement with the rail 13 so that the vent openings 20 of the rail will be effectively closed and sealed by the lower portion 31 of the plate 30 which thus forms a valve or closure. The upper portion 32 of the plate 30 overlies the ends of the lower portion 31 to provide the 20 downwardly facing shoulders 33 which rest upon the upper edges of the wall 16 for supporting the bottom edge of the plate out of engagement with the sill 9. The plate portion 32 terminates at its upper edge in an arcuate portion 34 which is disposed to curve inwardly and away from the storm sash 12 when the plate 30 is in its afore-described position as illustrated in Figure 3. To position the plate 30 to function as a deflector, said plate is drawn upwardly and thereby disengaged from the rollers 21, rotated a half turn and inserted between the rollers 22 and the wall 15 and with the lower portion 31 thereof disposed in the housing 14, as in its previously described position. With the closure portion 31 disposed against the inner side of the wall 15, as illustrated in Figure 4, it will be readily apparent that said closure portion will be spaced from the openings 20 so that air may pass freely through said openings and the air will be deflected upwardly by the plate 30 and back toward the storm sash 12, above the bottom rail 13 by the flared upper edge 34, which is disposed to extend toward the storm sash, due to the rotation of the plate 30. It will thus be readily apparent that the air entering the openings 20 will substantially follow the path as indicated by the arrows in Figure 4 and accordingly will enter the opening formed between the sill 9 and the raised lower sash 10 without creating a draft.

The rollers 22 are preferably formed of rubber or other relatively resilient material for yieldably retaining the plate 30 in its position of Figure 3 against the storm sash bar 13 for effectively closing the vent openings 20.

Various modifications and changes are contemplated and may obviously be resorted to, without departing from the spirit or scope of the invention as hereinafter defined by the appended claims.

We claim as our invention:

1. In combination with a window sash having a bottom rail provided with at least one vent opening, a housing secured to the inner side of said sash rail and with which said vent opening

communicates at its inner end, said housing having an inner side wall spaced from said sash rail and an open top, a combination closure and deflector plate insertable through said open top of the housing, a first means connected to and disposed in said housing adjacent the sash rail to engage and press a portion of the plate against the inner side of the sash rail for closing said vent opening, a second means connected to and disposed in said housing adjacent said inner side wall to engage and hold said plate portion against the inner side wall and out of engagement with the sash rail for admitting air to the housing through the vent opening, and said plate having a deflector portion extending upwardly from the housing and curved toward the sash, when the plate is disposed against said inner side wall, for deflecting the air rising from the housing back toward the window sash, said housing having end walls disposed substantially perpendicular to said sash rail and inner side wall, said first means and second means each comprising a pair of rollers journaled in the housing on said end walls.

2. In combination with a window sash having a bottom rail provided with at least one vent opening, a housing secured to the inner side of said sash rail and with which said vent opening communicates at its inner end, said housing having an inner side wall spaced from said sash rail and an open top, a combination closure and deflector plate insertable through said open top of the housing, a first means connected to and disposed in said housing adjacent the sash rail to engage and press a portion of the plate against the inner side of the sash rail for closing said vent opening, a second means connected to and disposed in said housing adjacent said inner side wall to engage and hold said plate portion against the inner side wall and out of engagement with the sash rail for admitting air to the housing through the vent opening, and said plate having a deflector portion extending upwardly from the housing and curved toward the sash, when the plate is disposed against said inner side wall, for deflecting the air rising from the housing back toward the window sash, said housing having end walls disposed substantially perpendicular to said sash rail and inner side wall, said first means and second means each comprising a pair of rollers journaled in the housing on said end walls, said rollers each being formed of a yieldable material for yieldably clamping the plate either against said sash rail or against the inner side wall.
